UNITED STATES PATENT OFFICE

2,539,109

COAL CONVEYING SYSTEM

Ernest C. Webb, Bay Village, Ohio, assignor to
Iron Fireman Manufacturing Company, Port-
land, Oreg.

Application August 6, 1945, Serial No. 609,159

1 Claim. (Cl. 302—22)

1

This invention relates generally to conveying systems, and particularly to a coal conveying system.

The main object of this invention is to provide a convenient, flexible and efficient means for moving solid fuel such as coal, from one point to another without forming an objectionable amount of dust and with the expenditure of the minimum amount of effort and power.

I accomplish these objects in the manner set forth in the following specification as illustrated in the accompanying drawing, in which is somewhat schematically shown a mechanical coal feeder 10 by means of which coal 11 is fed from a truck, freight car or bin (not shown) into an air duct 12, to which air is delivered by a fan 13 and carried to the separator 14, from which the solids 11 fall to the point of delivery. A return air pipe 15 extends from the separator 14 to the intake side of the fan 13, forming thereby a closed system. It is obvious that with such a system, some air would pass through the coal 11 and the feeder 10 and form an objectionable amount of dust in the surrounding atmosphere.

In order to prevent this condition, there is provided a bleeder pipe 16, which connects with the duct 12 between the feeder 10 and the fan 13. The bleeder pipe 16 discharges into a small cyclone 17, which removes the dust from it or bleeds from the system. This dust is accumulated in the container 18. It is desirable to provide the duct 12 with a butterfly valve 19 and the bleeder pipe 16 with a valve 20, by means of which valves 19 and 20 the relationship of air flow within the duct 12 and pipe 16 may be varied at will.

While the foregoing illustrates a representative form of the system, it must be understood that the details can be varied greatly to meet the conditions present, but in any event, the operation of the device tends to reduce the amount of dust given off with the coal at the point of delivery.

The foregoing is merely illustrative of an adaptation of the idea involved. With the present system, invention resides in the withdrawal of a portion of the conveying medium in order to reduce the amount of dust given off by the fuel at the point of discharge.

In a system of this kind the feeder 10 would be air tight and so designed as to create a slight suction or at least maintain a substantially atmospheric pressure at the discharge to prevent air from blowing back through the coal 11. It

is therefore assumed that the only place for air to enter or leave the system would be through the bleeder pipe 16 or through the discharge opening of the separator 14. Therefore, any air that is bled out of the system by the pipe 16 must be replaced by air entering the system at the separator 14. It is this feature which makes the apparatus function successfully.

To restate the matter, if there is a small amount of air sweeping over the coal pile and entering the cyclone 17 through its discharge opening, there is no possibility of dust blowing out through the opening of the cyclone 17. The amount of air entering the cyclone 17 is of course exactly equal to the amount of air being discharged through the bleeder pipe 16. It is therefore obvious that in order to accomplish its purpose, the bleeder pipe 16 may be located at any point on the pressure side of the system where the air pressure is sufficiently above atmospheric to cause the desired flow through the bleeder pipe 16 and cyclone 17.

While I have thus illustrated and described my invention, it is not my desire to be limited to the precise form shown herein, and I intend to cover such forms and modifications of the invention as fall fairly within the appended claim.

I claim:

1. In a pneumatic coal conveying system having a fan with an air inlet opening and an air outlet opening, a coal feeder with a coal discharge opening, a separator with a combined coal and air inlet opening, an air outlet opening, and a separate coal outlet opening, a first conduit connecting said fan outlet opening with said combined separator opening, a second conduit connecting said separator air outlet opening with said inlet opening of said fan, and a connection between said feeder discharge and said first conduit intermediate said fan and said separator, the provision for dustless discharge of said coal from said separator coal outlet opening which comprises means opening said first conduit to the atmosphere between said fan outlet and said feeder connection to said conduit, means for adjusting the resistance to air flow of said last mentioned means, and means in said first conduit between said atmospheric connection and said feeder connection for adjusting the resistance to air flow of said first conduit whereby by the manipulation of either or both of said air flow resistance adjusting means a controlled amount of air can be induced into said system through said coal outlet opening of said separator and an equivalent amount of air can be ejected from

2

said system to the atmosphere through said atmospheric connection to said first conduit.
